LIGHTING LOUVER

Robert A. D. Schwartz, Oakland, and Philip W. Pfeiffer, San Mateo, Calif., assignors to United Lighting and Ceiling Co., Oakland, Calif., a corporation of California

Filed Apr. 25, 1966, Ser. No. 1,998

Term of patent 14 years

Int. Cl. D26—06

U.S. Cl. D48—16

FIGURE 1 is a top plan view of a lighting louver showing our design;

FIGURE 2 is an end view taken in the plane indicated by line 2-2 of FIGURE 1;

FIGURE 3 is a cross-sectional view taken in the plane indicated by line 3-3 of FIGURE 1, and on an enlarged scale;

FIGURE 4 is a bottom plan view; and

FIGURE 5 is a side elevational view taken in the plane indicated by line 5-5 of FIGURE 4.

We claim:

The ornamental design for a lighting louver, substantially as shown.
